UNITED STATES PATENT OFFICE.

EDWARD ERICKSON, OF LYNN, MASSACHUSETTS, ASSIGNOR TO VICTOR SHOE MACHINERY CO., OF BOSTON, MASSACHUSETTS, A CORPORATION OF MASSACHUSETTS.

SHUTTLE-MOUNTING FOR SEWING-MACHINES.

1,182,842.

Specification of Letters Patent.

Patented May 9, 1916.

Original application filed July 20, 1914, Serial No. 852,103. Divided and this application filed March 27, 1915. Serial No. 17,944.

To all whom it may concern:

Be it known that I, EDWARD ERICKSON, a citizen of the United States of America, and a resident of Lynn, in the county of Essex 5 and State of Massachusetts, have invented certain new and useful Improvements in Shuttle-Mountings for Sewing-Machines, of which the following is a specification.

This invention relates to mountings for 10 sewing machine shuttles and has for its object the provision of frictional means for preventing the shuttle bobbin rotating too rapidly about its axis, the present application being a division of another application 15 of mine filed July 20, 1914 and numbered 852,103.

The invention consists of certain novel 20 features of construction and arrangement of parts which will be fully understood by reference to the description of the drawings 25 and to the claims hereinafter given.

Of the drawings: Figure 1 represents an 25 elevation of a mounting for shuttles embodying the principles of the present invention, said figure showing the shuttle in said mounting and a portion of the shuttle driving member, and Fig. 2 represents a section of the same, the cutting plane being on line 2—2 on Fig. 1.

30 Similar characters designate like parts throughout the figures of the drawings.

In the drawings, 14 is a shuttle casing in which is mounted a shuttle 15 having a bobbin recess 16 in one face thereof, and a 35 peripheral recess 17 adjacent to the hook 18 of said shuttle. This shuttle 15 is revoluble in the casing 14 and is prevented from accidental displacement therefrom by means of the plate 18 secured to the casing 14 by 40 means of the screws 19. Within the recess 16 is positioned a bobbin 20 adapted to rotate upon a spindle 21 forming a part of the shuttle 15. The outer face of the casing 14 has projecting therefrom ears 22 to which 45 is pivoted at 23, a bar 24, the free end of which extends beyond the casing 14 and has a notch 25 in the upper edge thereof. Secured to the front face of the shuttle casing 14 by means of a screw 26 is a latch 50 27 adapted to coact with the notch 25 to lock the bar 24 in position parallel to the shuttle 15 as indicated in Fig. 2 of the drawings.

The bar 24 has parallel openings 28 ex-

tending therethrough in each of which is 55 mounted a friction member such as the ball 29 pressed outwardly by means of the spring 30 in the opening 28. Behind each spring 30 is an adjusting member 31 threaded to the bar 24 and adapted to adjust the tension of the spring 30 in well-known manner.

When the bar 24 is in the position indicated in Fig. 2 of the drawings, the balls 29 bear against the outer face of the bobbin 65 20 and create sufficient friction thereon to prevent it from rotating too rapidly. The rapidity of rotation of the bobbin can be regulated by adjusting the tension of the springs 30 by means of the members 31. 70

The walls of the openings 30 at the mouth thereof are somewhat contracted to prevent the accidental displacement of the balls 29 when the bar 24 is unlocked to move about its pivot to permit of the removal of the 75 bobbin 20.

The shuttle 15 is operated by means of the lever 48 having a lateral lug 49 positioned in the recess 17.

It is believed that the operation and many 80 advantages of this invention will be fully understood from the foregoing description.

Having thus described my invention, I claim:

1. In a sewing machine, the combination 85 of a rotatably mounted shuttle provided with a bobbin recess; a bobbin therein; a shuttle supporting bracket; means engaging the closed side of said shuttle for imparting rotary movement thereto; a bar hinged to 90 said bracket and extending across the outer face of said bobbin, means for normally locking said bar to said bracket; and members supported by said bar and having frictional contact upon the face of said bobbin 95 on opposite sides of its center.

2. In a sewing machine, the combination 100 of a rotatably mounted shuttle provided with a bobbin recess; a bobbin therein; a shuttle supporting bracket; means engaging the closed side of said shuttle for imparting rotary movement thereto; a bar hinged to said bracket and extending across the outer face of said bobbin, means for normally locking said bar to said bracket; members 105 supported by said bar and having frictional contact upon the face of said bobbin; and means adjustably mounted on said bar for

regulating the frictional contact of said members.

3. In a sewing machine, the combination of a rotatably mounted shuttle provided with a bobbin recess; a bobbin therein; a shuttle supporting bracket; means engaging the closed side of said shuttle for imparting rotary movement thereto; a bar pivoted to said supporting bracket; means for locking said bar to said supporting bracket; and spring pressed balls carried by said bar and adapted to bear upon the outer face of said bobbin near the outer edge thereof.

4. In a sewing machine, the combination of a rotatably mounted shuttle provided with a bobbin recess; a bobbin therein; a shuttle supporting bracket; means engaging the closed side of said shuttle for imparting rotary movement thereto; a bar pivoted to said supporting member; means for locking said bar; spring pressed balls carried by said bar and adapted to bear upon the outer face of said bobbin; and means threaded to

said bar for adjusting the tension of said springs.

5. In a sewing machine, the combination of a rotatably mounted shuttle provided with a bobbin recess; a bobbin therein; a shuttle supporting bracket; means engaging said shuttle for imparting rotary movement thereto; a bar secured to said bracket and extending across the outer face of said bobbin, said bar having openings therethrough with inwardly extending lips at their inner ends; a ball in each opening in contact with the face of said bobbin; a spring in each opening normally forcing the ball against said lip; and a member threaded to said bar and adapted to regulate the tension of each spring.

Signed by me at 4 Post Office Sq., Boston, Mass., this 1st day of March, 1915.

EDWARD ERICKSON.
